(57) **CLAIM**

The ornamental design for a wagon rod holder as shown and described.

DESCRIPTION

FIG. 1 is a perspective view of a wagon rod holder showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a partial enlarged view of portion 9 in FIG. 1;

FIG. 10 is a partial enlarged view of portion 10 in FIG. 2; and,

FIG. 11 is a partial enlarged view of portion 11 in FIG. 4. The broken lines depict portions of the wagon rod holder and form no part of the claimed design.
